UNITED STATES PATENT OFFICE.

CLARENCE E. PRYOR, OF BINGHAMTON, NEW YORK.

TOUCH-REGULATOR FOR PIANOS.

No. 897,556.

Specification of Letters Patent.

Patented Sept. 1, 1908.

Application filed April 25, 1907. Serial No. 370,311.

To all whom it may concern:

Be it known that I, CLARENCE E. PRYOR, a citizen of the United States, residing at Binghamton, in the county of Broome and State of New York, have invented certain new and useful Improvements in Touch-Regulators for Pianos, of which the following is a specification.

My invention relates to improvements in key holding and touch regulating devices for pianos, in which hinged springs rest upon the key bars and are released and tightened by means of a hinged bar; also my device can be used to regulate touch for manual work.

It is to be observed that the rapid motion of the pneumatics in player pianos, or the rapid movements in manual work will cause a recoiling of the piano keys sufficient to interfere with the replacing of the jack in position under the butt, so as to destroy the rapid effect that is required of it. It is to be further observed that from the constant action of the end of the piano key upon the felt support beneath it there is a resultant wear which causes an audible play or rattle in the action of the parts. These various objections are obviated by my device. By the use of my invention the key is held rigid enough to overcome all these difficulties.

Therefore the object of my invention is to stop the rebound caused by the abstract dropping on the capstan screw when the abstract is released from delivering the hammer to the string and thus to make it possible to play the most rapid parts, by holding the key so that there is no rebounding effect; and also to increase or decrease the pressure on the keys, making it possible to manipulate the keys manually at the same time a player is in operation. The attachment can also be used to regulate the touch for manual work. I attain these objects by the mechanism illustrated in the accompanying drawing in which

Figure 1 is a sectional view of a piano action taken on the line 1, 1, of Fig. 2 showing the application of my invention. Fig. 2 is a broken plan view of a portion of a key board showing my invention applied. Fig. 3 is a detailed cross section showing my invention when it is out of action. Fig. 4, is a detail view of a slightly modified form of the invention.

Similar letters refer to similar parts throughout the several views.

The letter N, designates the piano action as a whole.

On the bed frame S, is the support T which extends the length of the key board; hinged upon this rest S, I have the bar or strip U attached to which is a curved arm V extending to the hinged point W, and at the point W, is connected the bar X which has a hinged connection at the other end at Y with the handle lever Z turning on the pivot Z². Beneath the hinged supporting bar U, is the curved spring U² fastened or attached to the hinged bar by having its end embedded therein or in any other suitable manner. The curved spring U² which has an intermediate curl 5 extends over and rests in a grooved plate 7, as shown in Figs. 1 and 2, which plate surmounts and is attached to the key bar H. By this flexible curved spring resting upon and surmounting the key bar at H, there is a gentle pressure continuously brought to bear upon the key bar which affects the action of the key. This curved spring U² and its bearing upon the key bar is adjustable so that the pressure upon the key bar may be increased or lessened or it may be thrown back, completely disengaged as shown in Fig. 3 if the manipulator so desires. To increase the pressure upon the key bar by the curved spring U², I pull forward the hand lever Z toward the front of the key G which pushes backward the bar X, which in turn pushes forward the curved bar V, which pushes down the hinged bar U, which in turn pushes down the end of the curved spring U² upon the grooved plate 7, thereby increasing the pressure of the curved spring upon the key at this point; and thus there is an increased resisting pressure upon the key which requires a stronger touch to manipulate. If I wish to make the manipulation of the key more easy, I push backward the handle lever Z.

If desired, the bar supporting the springs can be raised vertically as shown in Fig. 4, instead of being a hinged bar. By this device the pressure required to be used on the keys may be varied at will and at the same time the gentle constant pressure of the curved spring U² upon the key regulates the movement of the keys so as to permit the upright jack to assume its position under the butt, and thus keep in regular steady action all the parts; by this control of the key bar also the too free play and vibration of the key bar is completely obviated and the rattle or excessive play of the keys, no matter how

rapid the manipulation of the key board or how worn may be the felt key rest, is prevented.

This device may be applied to player pianos as well as all pianos. Some players or operators of player pianos are annoyed by the constant shake and rattle of the keys when they are playing the piano by the pneumatics. My invention can therefore be applied so as to hold the keys down rigidly while such pneumatic playing is in progress, or prevent any rattle of the keys during such playing. In player pianos the operator frequently desires to introduce some manual playing at the same time as he is playing all the pneumatics, in which case my device enables this voluntary manipulation by the player to be exercised without interfering in any way with the pneumatic action.

Having thus described my invention, what I claim as new, and for which I desire Letters Patent is as follows:

A touch regulator for pianos and the like

instruments comprising in combination with a longitudinal support arranged adjacent the rear inner ends of the keys, a bar hinged along one edge to said support, a lever arm carried by the end of said bar, means connected to said lever arm to rock the bar upon its pivotal center, and springs carried by the bar, said springs overhanging and adapted to engage the inner ends of the keys the bar having a longitudinal groove in its under face and being shouldered inward from the upper outer edge thereof, the springs being passed through the material of the bar at the base of the shouldered portion and having hooked ends embedded in the grooved portion in the under face of the bar.

In testimony whereof I have affixed my signature, in presence of two witnesses.

CLARENCE E. PRYOR.
